UNITED STATES PATENT OFFICE

161,579

TELEVISION STOOL OR SIMILAR ARTICLE

Eli W. Gaffield, Washington, D. C., assignor of thirty-three and one-third per cent to Raymond N. Matson, Silver Spring, Md.

Application May 19, 1950, Serial No. 10,048

Term of patent 14 years

(Cl. D15—8)

To all whom it may concern:

Be it known that I, Eli W. Gaffield, a citizen of the United States, residing at Washington, in the District of Columbia, have invented a new, original, and ornamental Design for a Television Stool or Similar Article, of which the following is a specification, reference being had to the accompanying drawing, forming a part thereof.

In the drawing,

Figure 1 is a side elevation of a television stool or similar article, showing my new design;

I claim:

The ornamental design for a television stool or similar article, as shown.

ELI W. GAFFIELD.
